UNITED STATES PATENT OFFICE.

HAZEL E. BREWER, OF SEATTLE, WASHINGTON.

COMBINATION GARMENT.

Application filed December 15, 1927. Serial No. 240,261.

This invention relates to body garments and the general object of the invention is to provide a single garment which fulfills the requirements of four separate garments, 5 namely a vest, undershirt or waist, bloomers, a brassière, and a girdle, and which fulfills these requirements in a manner more efficient and satisfactory than they are fulfilled by four separate garments.

10 Further objects of the invention are to provide an invention which reduces weight and bulk by eliminating overlapping of garments and surplus clothing, which will provide a single garment which is form fitting 15 so that there can be no bunched up clothing about the body and thus secure neater, smoother lines to the body and snugger fit to the figure.

A further object is to provide a garment 20 which will eliminate the usual elastic about the waist and hips commonly found in bloomers and girdles, thus reducing the unhealthful retarding of circulation caused by the use of tight elastic about the body.

25 A further and most important object is to provide a garment which will not bind and within which the body has perfect freedom of movement and particularly which eliminates pulling down about the waist 30 line which is the case where garters are connected to a girdle or corset, but it is so constructed that the strain or weight of supporting the stockings is placed entirely on the shoulders.

35 Further objects will appear in the course of the following description.

My invention is illustrated in the accompanying drawings, wherein:—

Figure 1 is a perspective view of the front 40 of the combination garment with the brassière unhooked;

Figure 2 is a rear view with the rear portion of the bloomers unbuttoned and hanging down;

45 Figure 3 is an inside elevation of the garment, the front and rear halves of the garment being opened out and the rear portion of the bloomers being unbuttoned;

Figure 4 is a detail view of the side 50 placket;

Figure 5 is a fragmentary side elevation showing the manner in which the fullness is secured for the rear portion of the bloomers.

Referring to these drawings, it will be 55 seen that the waist or upper portion of the garment is formed of two sections, 10 and 11,

which are vertically stitched at one side as at 12, the other side being open but being provided with hooks and eyes or other fastening means designated 13 whereby this 60 side of the girdle, waist or brassière may be fastened. To the lower end of the section 11 there is stitched the front portion 14 of the bloomers. These bloomers are, of course, made rather full, and the rear section of the 65 bloomers which is designated 15 is stitched at its lateral margins to the lateral margins of the lower portion of the front section 14 along the line indicated at 16. The upper half of the rear section, however, is not so 70 stitched, but the hem of this section is provided with button holes 19 whereby the upper portion of the rear section may be fastened up in place or unbuttoned and lowered as shown in Figure 2 or unbuttoned from 75 the side. In order to provide for the proper fullness of the bloomers at the crotch, the front section 14 as shown in Figure 5 is provided with a relatively deep V-cut 18 and the rear section 15 as shown in this figure is 80 formed with a straight edge 19 which is stitched to the margins of the V-cut.

Preferably a flap 20 is provided at each placket which extends downward from the waist or brassière and which extends beneath the lateral margin of the upper portion 85 of the rear section 15 when the latter is buttoned up as shown in Figure 4.

Stitched to the rear section 10 of the brassière are the upper portions of a suspender 90 element 21. This suspender element is formed preferably of two thicknesses of cloth, though one thickness may be used, and this cloth is cut out at its upper end to provide two upwardly extending tapering 95 portions 22. The suspender element 21 extends below the waist line of the rear section 10 and is also cut to provide two downwardly tapering or downwardly narrowing elongated webs or portions 23 to which the 100 elastic garters 24 may be attached in any suitable manner. These garters 24 have snap clasps at their lower ends or other means for engagement with the stockings.

It will be seen that this lower portion of the 105 suspender element is cut out at its middle 25 to provide these two downwardly tapering or narrowing portions 23. These portions 23 are entirely free of attachment but the portions 22 are stitched all around their 110 margins to the section 10 as at 26. The front section 11 is also provided with a sus-

5 pender element 27 constructed in the same manner as the suspender element 21 and having the two upwardly extending and narrowing portions 28 which are stitched around their margins as to the front section 11 and the two downwardly extending portions 29 which are entirely free from the garment and which have attached thereto the garters 24 such as previously described.

10 The portions 29 are separated by the upwardly extending cut 30 which corresponds to the upwardly extending cut 25. It will be noted in Figure 3 that the width of the suspender element 21 between the medially disposed cut away portions is wider than is the case with the element 27. Attached to the portions 22 and 28 are the connecting straps 31 which arch over the shoulders as shown in Figure 1 when the garment is in place, and thus the whole weight of the garment is supported from the shoulders and the downward pull of the stockings is supported entirely by the shoulders. Preferably the extremities of these straps are inserted between the thickness of material 22 or 28 and the body section 10 or 11 and, of course, stitched to the body section and to these portions 22 and 28.

15 It will be noted that these suspender portions 23 and 29 are widened to the full width of the waist line and attached at this point to the brassière. This gives additional strength to the garment where, at the point called upon, it will stand a greater strain. From the waist line upward the suspender elements are tapered to the desired width to receive a narrow shoulder strap. These shoulder straps are at the top of the brassière, thus causing the suspender arrangement to conform to the form fitting features of the brassière and to add only the necessary thickness of material through the body. The front and back of the suspender arrangement are the same except that the back has the additional feature of extending downward from the middle of the waist line a sufficient distance to prevent any gap between the back of the brassière and the back of the bloomers attached thereto. The 20 whole suspender arrangement with the detachable garters is so constructed that there is a straight pull from the shoulders to the garters and the gradual widening of the suspender attachment from the shoulders to the waist line and from the garters to the waist line utilizes this pull to hold or urge into proper shape, the bust, stomach, abdomen and hips. In any garment having a device for the purpose of supporting stockings, which device consists of a narrow strip sewed to the body of the garment, the pull that is exerted between the shoulders and the garters will draw the garment away from the body at the point where the strap 25 is attached to the garment, but the suspender

arrangement or hose supporter of this garment is widened to encircle the entire waist line and is sewed to the waist line and the brassière and this causes the pull between the shoulders and the garters to draw the garment in toward the body, making it fit snugly and comfortably without pulling or binding at any point. This is a very important feature of my improved garment.

20 It is to be noted that in the bloomer portion of the garment, the top edge of the bloomers, both front and back, is to be cut on the bias so as to give a little fullness about the waist line and provide fullness for the hips and legs. There is no seam in the center, front or back which thus eliminates binding against the body of the wearer.

25 The construction of the crotch as shown in Figures 1 and 5 is such that when the front and back are joined together they 30 form a straight line as a petticoat, making it unnecessary to wear a petticoat except with the sheerest of clothing.

35 I claim:

1. A body garment comprising a waist portion constituting a brassière and open beneath the arm for the full length of the waist portion, said opening having means whereby the opening may be held closed, bloomers having a front portion permanently attached to the waist portion, said bloomers having a seat portion partly separated at the sides from the front portion of the bloomers and entirely separated at the top from the waist, and suspender elements 40 attached to the inside faces of the front and rear of the waist and extending upward from the lower end of the waist to the top thereof and cut to provide two upwardly extending webs and two downwardly depending webs for the front and rear of the waist, said suspender elements at the waist band of the waist having a width co-terminous with the waist band measurement and said webs gradually diminishing from 45 the waist line to the upper ends and having shoulder straps forming continuations thereof, the webs being stitched to the waist throughout their entire extent, the depending webs depending freely into the bloomers and being provided with elastic straps having 50 hose engaging means.

55 2. A body garment comprising a waist portion constituting a brassière and terminating at the waist, bloomers attached to the waist portion and having a seat section partly separated at the sides from the front of the bloomers and entirely separated at the top from the waist section, and suspender elements attached to the inside of the front and back of the waist and having a width at the waist line equal to the waist line of the waist, said suspender elements being formed to provide two upwardly extending webs for the front section and 60

two upwardly extending webs for the back section of the waist, the webs being stitched to the waist throughout their entire extent, said suspender elements being further formed to provide two pairs of depending webs, one pair at the front and one at the back of the waist, the webs of each pair being separated from each other by a cut-away portion, the cut-away portion be-

tween the rear webs being shorter than the 10 cut-away portions between the front web whereby the seat of the bloomers may overlap the suspending element at the rear of the waist.

In testimony whereof I hereunto affix my 15 signature.

HAZEL E. BREWER.
